COMBINED BAROMETER, THERMOMETER, AND HYGROMETER

John Cuccio, Westport, Conn., assignor to Sybron
Corporation, Rochester, N.Y.

Filed Nov. 15, 1971, Ser. No. 199,077

Term of patent 14 years

Int. Cl. D10—04

U.S. Cl. D52—7 R

FIG. 1

FIG. 2

FIG. 3

FIG. 4

FIG. 1 is a top plan view of a combined barometer, thermometer and hygrometer showing my new design;

FIG. 2 is a front elevational view thereof;

FIG. 3 is a rear elevation view thereof; and

FIG. 4 is a left side elevational view, the right side being a mirror image thereof.

I claim:

The ornamental design for a combined barometer, thermometer and hygrometer, substantially as shown and described.
